CLAIM

The ornamental design for a vehicle windshield, as shown and described.

DESCRIPTION

FIG. 1 is a top-down plan view of a vehicle windshield showing my new design;

FIG. 2 is a bottom-up plan view thereof;

FIG. 3 is a front elevational view thereof;

FIG. 4 is a left side elevational view thereof;

FIG. 5 is a right side elevational view thereof;

FIG. 6 is a section of the vehicle windshield taken along the lines 6—6 in FIG. 3;

FIG. 7 is a top edge view thereof;

FIG. 8 is a bottom edge view thereof;

FIG. 9 is a top down plan view plan view of the vehicle windshield;

FIG. 10 is a left side elevational view thereof;

FIG. 11 is a front elevational view of an alternative embodiment of the vehicle windshield illustrated in FIGS. 1–10, further including a black ceramic paint applied to the inner (bottom) surface of the vehicle windshield;

FIG. 12 is a rear elevational view thereof; and,

FIG. 13 is a bottom-up plan view thereof.

The broken lines shown in the drawings are for illustrative purposes only and form no part of the claimed invention.
